CLAIM

The ornamental design for a backframe for self-contained breathing apparatus, as shown and described.

DESCRIPTION

FIG. 1 is a perspective view showing an embodiment of the new design for a backframe for self-contained breathing apparatus;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing forms no part of the claimed design, and the shading is provided to illustrate contour only and is not an indication of texture, gloss, etc.

1 Claim, 5 Drawing Sheets
